DESIGN FOR A WHEELED TOY

Harry S. Tucker, Cleveland Heights, Ohio

Application August 2, 1944, Serial No. 114,692

Term of patent 3½ years

(Cl. D34—15)

To all whom it may concern:

Be it known that I, Harry S. Tucker, a citizen of the United States, residing at Cleveland Heights, county of Cuyahoga and State of Ohio, having invented a new, original, and ornamental Design for Wheeled Toys, of which the following is a specification, reference being had to the accompanying drawing, forming part thereof.

Fig. 1 is a side elevational view of a wheeled toy, showing my new design;

Fig. 2 is a top plan view;
Fig. 3 is a front elevational view, and
Fig. 4 is a rear elevational view thereof.
The drawing is lined to indicate coloring.
I claim:
The ornamental design for a wheeled toy, substantially as shown and described.

HARRY S. TUCKER.
